(57) **CLAIM**

The ornamental design for the direct broadcast satellite antenna feedhorn with mounting arm, as shown and described.

DESCRIPTION

FIG. 1 is a perspective view of our new direct broadcast satellite antenna feedhorn with mounting arm design shown offset mounted on a satellite antenna;

FIG. 2 is a front elevational view thereof;

FIG. 3 is a side elevational view thereof with the opposite side a mirror image thereof;

FIG. 4 is a rear elevational view thereof;

FIG. 5 is a top plan view thereof; and,

FIG. 6 is a bottom plan view thereof.

The characteristic features of the design resides in the flowing curves of the outer surface of the feedhorn and the convex surface along the side of the mounting arm.

The broken line showing of the dish and mounting in FIG. 1 is for illustrative purposes only and forms no part of the claimed design.
